UNITED STATES PATENT OFFICE.

EDWARD PAYSON COWLES, OF SPARTA, MICHIGAN.

AUTOMATICALLY-REVERSING DRAIN BOARD FOR CLOTHES WRINGERS.

Application filed June 25, 1920. Serial No. 391,657.

To all whom it may concern:

Be it known that I, EDWARD PAYSON COWLES, a citizen of the United States, and residing at Sparta, Kent County, State of Michigan, have invented certain new and useful Improvements in Automatically-Reversing Drain Boards for Clothes Wringers, of which the following is a specification.

This invention relates to wringers and particularly to wringers driven by power means in either direction, that is, in which the direction of movement of the pressure rollers may be reversed when desired so that the liquid squeezed out of the cloth garments or other articles passing between the rollers may be caused to fall on either side of the rollers. It is common practice to employ with wringers of this type drain-boards, which are usually pivotally supported beneath the rollers in the path of the falling liquid, and are adapted to be tilted in either direction, depending upon the direction of rotation of the rollers to throw the liquid back into the compartment from which the wet garments were drawn. In other words, these drain boards are reversible.

Heretofore, drain-boards of this character have generally been manually operated, that is, they have been arranged to be reversed by hand by the operator of the wringer when the direction of rotation of the rollers is changed, so that they direct the falling liquid in the proper direction. In certain instances the drain boards have been frictionally connected to the rollers so that as the rollers are reversed the drain board will simultaneously be reversed. It has been the experience of persons operating wringers in which the drain board does not automatically reverse that, either through mistake or forgetfulness, the wringers have often been operated at times with the drain-board turned in the wrong direction thereby throwing the suds into the rinse water, the rinse water into the bluing water, or the bluing water into the dry clothes, causing delay, repetition, and adding to the cost of operation. This mistake is often made by even most experienced operators. Also, in prior types of automatically reversing drain boards, having frictional connection with the rollers, this connection becomes worn after considerable usage and the board fails to reverse properly. Also the presence of soap and water on the rollers and supporting shafts thoroughly lubricates the same to

prevent efficient operation of any reversing mechanism which is only frictionally connected to the rollers or operating gear.

It is the object of this invention therefore to provide an attachment for wringers, particularly power wringers, which will automatically reverse the position of the drain-board whenever the direction of rotation of the rollers is changed so that the drain-board will always be turned in the right direction and no mistake can be made even by the most inexperienced operator.

The invention may be embodied in a number of different forms and several of these forms are disclosed in the following description, when taken in connection with the following drawings in which:

Figure 1 is a side view of portion of one form of power wringer showing the driving and reversing gear and the mechanism for automatically reversing the drain-board;

Figure 2 is a section along the line 2-2 of Figure 1;

Figure 3 is a side view, with parts broken away, of portion of a wringer having a chain and sprocket drive, the reversing mechanism however, not being illustrated;

Figure 4 is a section on the line 4-4 of Figure 3;

Figure 5 is an end view of another form of wringer having the invention incorporated therewith, the roller driving mechanism having been omitted.

Figure 6 is a section on line 6-6 of Figure 5.

Referring particularly to Figure 1, it will be seen that the roller 10 is connected to a power shaft 11 through driving and reversing gearing indicated generally at G. Gear- ing of this type is commonly used on wringing machines and requires no specific description. The clutch member 12 of this mechanism is adapted to be moved back and forth along the shaft 13 by means of an operating handle 14 in reversing the direction of drive, and the shaft 13 is connected by a coupling 15 to the shaft 16 which supports one end of the roller 10 and is rigid therewith.

The drain-board is illustrated at 17 and this board is pivotally supported on trunnions 18 journaled in the frame of the wringer. A shaft 19 having a squared end 20 engaging a squared recess in the drain-board and trunnion, is journaled near one end in the frame of the wringer and at its

other end in the metallic frame of the driving and reversing gear G. This shaft 19 is rotatable with the drain-board and has, intermediate its ends, a downwardly extending slotted portion 21. Within this slot is positioned a plate 22 pivoted to the member 19 at 23 and having its upper end which extends from the mouth of the slot, divided into three portions 24, 25 and 26 respectively. The arms 24 and 25 are curved in opposite directions, as illustrated clearly in Figure 2, and the central arm 26 extends laterally and upwardly and has pivotally connected thereto at its outer end one end of a rod 27, the other end of this rod being connected to an extension 14^a of the operating lever 14. By means of this connecting rod the plate 22 is rocked back and forth around the pivot 23 as the arm 14 is moved, in reversing the direction of drive of the rollers. In order that the pull of rod 27 exert no eccentric force on the arm 26 which would tend to cause the plate 22 to bind in the slot, the pivot bolt 23 is extended and the outer end of the arm 26 connected by the member 26 to the outer end of the bolt.

The coupling member 15 is provided with radially extending lugs 15^a, 15^b, which follow a constant circular path as the coupling 30 15 revolves. In the operation of the device, assuming the lever to be in the position illustrated in Figure 1 and the driven roller 10 to be rotating in the direction of the arrow, Figures 1 and 2, it will be seen that the arm 35 25 is disposed in the same vertical plane as the rapidly rotating lugs 15^a, 15^b, but out of their reach. This position of the various parts will be maintained until the lever 14 is operated to change the direction of the 40 rod. In this case the plate 22 would be drawn to the right, Figure 1, until the arm 24 lies directly in the path of the lugs which begin to rotate in the opposite direction as soon as the clutch member 12 has been shifted to the right. During the half revolution 45 of coupling 15 in the new direction one of these lugs will strike the upper end of the arm 24 and will rotate the shaft 19 about its axis to reverse the drain. A flat spring 50 28 secured to the board bears down upon the usual cross rod 29 and serves to complete the motion of reversing, after the center of the spring has been moved across the rod. Cross pieces 30 and 31 attached to the frame 55 limit the movement of the drain-board in the usual manner.

In certain types of wringers the drain-board is easily tipped from side to side and in such cases it is not necessary to have power operated reversing mechanism. In such cases the operating handle may be directly connected by means of rods or levers to the drain-board. Wherever restraining devices, such as the spring 28 are utilized, 60 however, it is desirable to have the tipping

of the board accomplished by power mechanism so that the handle 14 may be easily moved.

In the form of the invention illustrated in figures 3 and 4, the roller 10' is driven by a sprocket on the outer end of the shaft 13' and the mechanism for reversing the direction of rotation of the sprocket and roller is not illustrated. Any common form of reversing mechanism may be used for this purpose. Pivotedly mounted at 23' and positioned between the parallel plates of this bracket 41 is a plate 22' having upwardly and laterally extending arms 24' and 25'. This plate 22' also has at its lower end a horizontally extending arm 42 which is normally pulled downwardly by its weighted end 43. The movement of the plate 22' around its pivotal point under the influence of the weight 43 is limited by the solid end 44 of shaft 19' to which the plates 41 are rigidly secured. On the coupling member 15' are positioned lugs 15^a, 15^b, which are square at one end and pointed at the other, as illustrated, and disposed in different vertical planes with their pointed ends directed towards each other.

Assuming the roller 10' to be rotating in the direction of the arrows, it will be seen that the lug 15^a will not contact with the arm 25' but that the lug 15^b will contact at each revolution with the lug 24'. Inasmuch however as the pointed edge of the lug 15^b is slightly offset from the face of the arm 24', this lug will simply act as a wedge, tipping the plate 22' outwardly against the action of the weight 43, and allowing it to fall back as soon as the lug has passed by. Whenever the direction of rotation of the sprocket and shaft 13 is changed however the lug 15^a, rotating in the opposite direction, will present its flat rear end to the arm 24' which will be engaged thereby and the plate 22', the shaft 19', and drain-board 17' rotated. The flat spring 28' completes the reversing movement in either direction and cross bars 30' and 31' serve as stops limiting the extent of movement of the board.

In Figure 5 is illustrated a modification designed for use on wringers in which no coupling member such as member 15 or 15', of the two forms above described, is employed. In this form also the drain-board is pivoted on a cross bar 50, which is located at a considerable distance below it, and rigidly connected to the bracket 51 upon which the drain-board is mounted is a frame 22'' having upwardly extending arms 24'' and 25'' offset from each other as are arms 24' and 25' of the form illustrated in Figs. 3 and 4. Pivotedly secured to the gear wheel 52, which is one of the driving gears of the roller, are two pawls 15^a, and 15^b, the outer ends of these pawls swinging toward and away from the shaft 13'' under the influence of gravity.

as the gear 52 revolves, the pawls being also offset, as are arms 24" and 25", so that pawl 15^e is in the same transverse vertical plane as arm 25" and pawl 15^e is in the same vertical plane as arm 24". The outward movement of the pawls is limited, as their inclined base portions strike against the opposite sides of the tapered radially extending rib 55.

10 With the gear 52 rotating in the direction of the arrow the pawl 15^e will not engage either arm 24" or arm 25" but the back of pawl 15^e will engage and ride over the end of arm 24" at each revolution. Whenever 15 the direction of rotation of the gear 52 is changed however it will be seen that the pawl 15^e will engage the arm 24" and throw the drain-board to dotted line position, the flat spring 28" being instrumental in completing the movement, as in the other forms 20 described, when the direction of rotation is again reversed the pawl 15^e will engage arm 25" and return the board to full line position. The cross rod 29", which cooperates 25 with the spring 28" is, as illustrated, positioned to extend through the central opening in the frame 22' and the usual cross rods 30" and 31" are provided to limit the rotary movement of the drain-board.

30 Because of the manner of pivoting this board it will be seen that in its reversing movement it is not only oppositely tilted but is also laterally extended for a considerable distance. In certain forms of wringers it 35 is very desirable to have the drain-board extended in this manner.

It is obvious that my invention may be illustrated in still other forms and I do not therefore desire to limit the invention to 40 either of the forms described and illustrated, its scope being indicated in the appended claims.

Having thus described my invention what

I claim as new and desire to secure by Letters Patent is:

45

1. In a wringer, a roller adapted to be driven in either direction, a reversible drain-board, means for driving said roller in either direction, said means including a rotatable member having a cam, and means for reversing the drain-board when the direction of drive is changed, said last mentioned means including a member adapted to be engaged by said cam when the direction of drive is changed.

50

2. In a wringer, a roller adapted to be driven in either direction, a reversible drain-board, a rotatable member connected to said roller, two spaced cams on said rotatable member, and members connected to said drain-board and arranged to be engaged by said cams, one of said members being engaged by the corresponding cam to reverse the board, whenever the driving means is reversed.

55

3. In a wringer, in combination, a roller, a reversible drain-board having spaced arms, rigidly secured thereto, a rotatable member connected to the roller, and spaced cams mounted on said member, one of said cams being adapted to engage one of said arms whenever the drive mechanism is reversed, whereby the drain-board is automatically reversed.

60

4. In a wringer, in combination, a roller, a reversible drain-board, spaced arms rigidly connected to said drain-board, mechanism including a rotatable member for driving said roller in either direction, and two oppositely directed cams pivotally secured to said rotatable member, one of said cams being adapted to engage one of said arms whenever the drive mechanism is reversed, whereby the drain-board is automatically reversed.

65

In testimony whereof I affix my signature.

EDWARD PAYSON COWLES.
